UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

STOCKING AND METHOD OF KNITTING THE SAME.

1,194,675.

Specification of Letters Patent. Patented Aug. 15, 1916.

Application filed April 28, 1916. Serial No. 94,232.

To all whom it may concern:

Be it known that I, ROBERT W. SCOTT, a citizen of the United States, and resident of Boston, in the county of Suffolk and State of Massachusetts, have invented new and useful Improvements in Stockings and Methods of Knitting the Same, of which the following is a specification.

This invention relates to the manufacture of stockings. I shall describe as one instance thereof a stocking and the process of making it, said stocking being tubular throughout, having ordinary seamless toe and heel pockets, and having the leg portion knit with double the number of wales contained in the foot portion, the whole fabric being composed of non-rib stitches; that is to say, all of the stitches being drawn to the same faces of the fabric. The process will be described in connection with the various steps taken in the formation of such a stocking, as one particular instance only of the products resulting from its practice.

In the accompanying drawing, —Figure 1 is a diagram plan of a circular series of knitting needles, for instance, of the needles employed in a machine upon which my process is adapted to be practised and my article to be produced; Fig. 2 is a diagram plan illustrating one arrangement of multiple yarn feed; Fig. 3 is a diagram view illustrating a typical stocking in elevation; and Figs. 4 and 5 are respectively enlarged diagrams of the fabric for the foot and for the leg.

Figure 1 represents in diagram a circular set of needles, the large circles A representing a series of needles capable of being retired from action without holding stitches, the small circles B representing needles which may be maintained constantly in active knitting position. The small circles B¹ represent a series of needles which at will may be rendered active, or retired with stitches upon them.

The stocking is preferably made upon a 2-feed machine, and these feeds may be located in respect of the circle of needles as illustrated in Fig. 2. One of these may be a main feed, as at Y, and the other an auxiliary feed, as at X. In forming the stocking, according to this invention, knitting is preferably commenced upon the naked needles and a selvage structure s, Fig. 3, formed in accordance, for instance, with the

disclosure of my Letters Patent No. 1,375,2 reissued June 16, 1914. After this selvage structure is formed, preferably with yarn y from the main feed Y, an extent of tubular fabric f is knitted prior to the commencement of the toe-pocket, which may be subsequently raveled away in the process of closing the toe-gap. These courses are knit upon one-half the needles only; for instance, those marked B and B¹ in Fig. 1, the intervening needles A in said figure being retired with no stitches upon them.

The toe is knit following the well-known method in the production of seamless heel and toe pouches. At the completion of the toe, the foot F is knit in circular courses of the yarn y such as shown in Fig. 4, on the same active needles B and B¹, and the heel is knit in the same way as the toe-pouch. At the end of the heel knitting, a few circular courses c are formed, and then the character of the fabric is changed by restoring the inactive needles A to working position, so that all needles will take thread and knit at the main feed Y; and, at the supplemental feed, X, the needles are so manipulated that the needles A only take thread x and knit, the intervening needles B and B¹ passing below the yarn receiving level. This arrangement results in the production of a fabric commonly known as accordion fabric an instance of which is shown in Fig. 5. This fabric is produced to a sufficient extent to form the leg L of the stocking.

If it is desired to form a welt at the top of the leg, this result may be brought about by following the disclosure of my Letters Patent No. 1,045,620, dated November 26, 1912, which results in an out-turned welt W, or the disclosure of my Letters Patent No. 1,037,669, dated September 3, 1912, may be practised, in which case an inturned welt will be formed. In either case, it will be noted, after the section of the welted fabric 100 is attached to the main web, it is necessary, in order to fasten the binding stitches, to knit a short section of tubular fabric before pressing the work from the needles, as disclosed in said Patent No. 1,037,669. In the 105 case of an out-turned welt, the welted portion will contain the same number of wales as the foot portion of the stocking; but in the case of an inturned welt, it may contain double this number of wales, that is to 110

say, the same number as contained in the leg portion of the stocking. It is preferable to effect changes of yarn at those points where the character of the fabric is changed, 5 for instance, at the point above the heel, and, again, at the beginning of the welt. Finer yarns may be employed, for instance, in the leg L than in the foot, and a coarser yarn than either of those in the leg may be 10 employed in the welt.

The beginning selvage may be formed by manipulating needles B and B¹ only, needles B¹ being retired while needles B are active, or it may be formed by retiring needles A 15 while both needles B and B¹ are active. In the latter case, needles A should be pressed off and retired after the selvage is formed, the knitting for the tubular fabric f and foot F in either case proceeding upon 20 current or alternate needles only. When the knitting is completed, the stocking is finished by looping the toe-seam as usual, the selvaged tubular fabric f being raveled away during or prior to forming the seam. 25 For this purpose the selvage may be cut off or cut or broken through, or one of the courses may be drawn out, in order to release a free raveling subsequent course.

What I claim is:

30 1. A seamless stocking knit from toe to top comprising a seamless toe, foot and heel of plain fabric, and a tubular leg continuous with foot and heel of multiple course accordion fabric having a greater number 35 of wales than the foot.

2. A seamless stocking blank knit from toe to top comprising a beginning selvage, a short section of tubular fabric, a seamless toe, foot and heel of plain fabric, and a 40 tubular leg continuous with foot and heel of multiple course accordion fabric having a greater number of wales than the foot.

3. A seamless stocking knit from toe to top comprising a toe, foot and heel of plain 45 fabric, a tubular leg continuous with foot and heel of multiple course accordion fabric having a greater number of wales than the foot, and an integral welt at the top followed by a short section of tubular fabric.

50 4. A seamless stocking blank knit from toe to top comprising a beginning selvage, a short section of tubular fabric, a toe, foot and heel of plain fabric, a tubular leg continuous with foot and heel of multiple 55 course accordion fabric having a greater number of wales than the foot, and an integral welt at the top followed by a short section of tubular fabric.

5. A seamless stocking blank knit from toe to top comprising a beginning selvage, a short section of tubular fabric of a certain 60 number of wales, a seamless toe, foot and heel of plain fabric of the same number of wales and relatively coarse yarn, and a tubular leg continuous with foot and heel of

multiple course accordion fabric or finer yarns than the foot having a greater number of wales than the foot.

6. The art of knitting a seamless stocking on a circle of needles comprising knitting a seamless toe pouch, foot, and heel on some of the needles only; and thereafter knitting in continuation thereof on said needles and intervening needles a seamless leg of multiple-feed accordion fabric. 70

7. The art of knitting a seamless stocking on a circle of needles comprising knitting an extent of tubular fabric on some of the needles only, the intervening needles being retired, thereafter knitting a seamless toe pouch, foot, and heel on some of the needles only; and thereafter knitting in continuation thereof on said needles and intervening needles a seamless leg of multiple-feed accordion fabric. 75

8. The art of knitting a seamless stocking on a circle of needles comprising first forming a selvage on the naked needles, then knitting an extent of tubular fabric on some of the needles only, the intervening needles being retired, thereafter knitting a seamless toe pouch, foot, and heel on some of the needles only; and thereafter knitting in continuation thereof on said needles and intervening needles a seamless leg of multiple-feed accordion fabric. 80

9. The art of knitting a seamless stocking on a circle of needles comprising first forming a selvage on the naked needles, then knitting an extent of tubular fabric on some 85

of the needles only, the intervening needles being retired, thereafter knitting a seamless toe pouch, foot, and heel on some of the needles only; and thereafter knitting in continuation thereof on said needles and intervening needles a seamless leg of multiple-feed accordion fabric; and thereafter finishing the stocking by looping the toe-seam and raveling away the selvaged tubular section of fabric first formed. 90

10. The art of knitting a seamless stocking on a circle of needles comprising first forming a selvage on the naked needles, then knitting an extent of tubular fabric on some of the needles only, the intervening needles being retired; thereafter knitting a seamless toe pouch, foot and heel on some of the needles only; and thereafter knitting in continuation thereof on said needles and intervening needles a seamless leg of multiple-feed accordion fabric; thereafter forming an integral welt, then knitting a subsequent section of fabric, and then pressing-off the stocking. 110

11. The art of knitting a seamless stocking on a circle of needles comprising first forming a selvage on the naked needles, then knitting an extent of tubular fabric on some of the needles only, the intervening needles being retired; thereafter knitting a seam- 115

less toe pouch, foot, and heel on some of the needles only; thereafter knitting in continuation thereof on said needles and intervening needles a seamless leg of multiple-feed accordion fabric; thereafter forming an integral welt, then knitting a subsequent section of fabric, then pressing-off the stocking, and thereafter finishing the stocking by

5 looping the toe seam and raveling away the selvaged section of fabric preceding the toe. 10

Signed by me at Boston, Massachusetts, this twenty sixth day of April, 1916.

ROBERT W. SCOTT.
